UNITED STATES PATENT OFFICE.

ALEXIS FRANÇOIS DE SAINT-ROMAIN, OF ST.-ETIENNE, LOIRE, FRANCE.

ADVERTISING APPARATUS.

1,165,397.

Specification of Letters Patent. Patented Dec. 28, 1915.

Application filed April 21, 1914. Serial No. 833,393.

To all whom it may concern:

Be it known that I, ALEXIS FRANÇOIS DE SAINT-ROMAIN, a citizen of the Republic of France, and a resident of 4 Rue Marengo, 5 St.-Etienne, Loire, France, have invented a new and useful Advertising Apparatus, of which the following is a specification.

This invention relates to advertising or display apparatus of the changing type, 10 comprising a window in front of which are presented in succession various advertising panels. It is characterized by this that the panels are independent and that each panel undergoes a turning-over between two successive presentations so as to show alternately its two faces.

A method of carrying out this invention has been shown by way of example upon the annexed drawing in which:

20 Figure 1 is a front view of the apparatus. Fig. 2 is a section on line 2—2 of Fig. 1 seen from the right. On a larger scale, Fig. 3 is a detail of the transmission device in engagement with the pinion, and Figs. 4 and 25 5 show the two different positions of another device of the apparatus.

The apparatus is of the shape of a parallelepipedal box; the front face A of the box carries a glass window through which 30 the advertising panels are visible. Adjacent each side wall A' (Figs. 1 and 2) is an endless chain B stretching between two toothed wheels B' B². This chain B of which a detail is shown in Fig. 3 is provided with grooves between its joints, the 35 links being thus approximately semi-circular in shape. Two pinions C and C' also mesh with the chain B. A rail or slope D, forming an inclined plane between the pinions C and C', is fixed to each wall A. Above this inclined plane is arranged an escapement device E.

At the lower part of each wall A' (Fig. 45 2), there are fixed a guide device F and a switch point F', which latter is movable around a horizontal axis f. At the upper part of each wall A' there is fixed above the pinion C a detaching block or tappet G.

The toothed wheels B' are keyed upon 50 a cross shaft b (Fig. 1) and the toothed wheels B² upon another shaft b'. Further the escapement devices E are fixed to a cross shaft e. These parts thus work together and their movements are thus synchronized.

55 The extremities of the canvases or fabric backings H, upon which are fixed the ad-

vertising panels, are secured to wires or rods I and I' (Fig. 2). These rods or wires I and I' are provided at their extremities with rollers i.

The toothed wheels B' B² and the pinions C and C' are each formed in two parts having the same number of teeth; one enters into engagement with the chain B and the other receives the wires I and I'. These two parts are assembled together in such a manner that the solid portions of the part which receives the wires correspond to the hollow portions of the other. The solid portions of the part in engagement with the chain are 60 hollowed out in so far as is necessary to afford passages to the wires and to permit the organs, rollers, rails, switches and tappets or disengaging blocks to be brought outside the planes of the chain. It follows that 65 the wires, which can locate themselves only in the hollows of the gear-teeth and out of engagement with the chain, always place themselves correctly in the hollowed-out portions of the chain B.

70 The working of the apparatus is as follows:—By rotation of the toothed wheels B' B² in the direction of the arrows (Fig. 2) a finger or striker e' carried by the chain B acts through bell crank e² periodically 75 upon the control of the escapement devices E which release the first of the upper wires I. This wire I enters into engagement by reason of the inclinations of the rail with the distributor pinions C' which guide it into 80 the hollows of the chain B. The corresponding lower wire follows the movement of descent, enters into engagement with the pinions B² and locates itself in its turn in the opened-out portions of the chain B. The 85 movement continuing, the wire I' comes first into contact with the switch tongues F' (position of Fig. 4) slips past them and brings 90 them to the position of Fig. 5. Still in engagement with the chain, the wire I' reaches the upper part of the apparatus, meets the 95 detaching or disengaging block G, is removed from the chains and again assumes its position upon the inclined plane. The wire I which has been following, meets the switch tongues F' in the position of Fig. 100 5. These switch tongues throw back the wire I out of the chains and again take up the position shown in Fig. 4. The same 105 operation takes place for each panel. It 110 will be seen then that the panel H has been brought back to the rear in a reversed or in-

verted position, the wire I being at the bottom and the wire I' at the top, while for the face H' which was visible in the original position there is substituted the face H² which 5 will be visible at the time of the second passing of the canvas H in front of the window. By this means one can thus utilize the two faces, back and front, of each canvas H.

It is evident that the invention is not limited to the detail of construction shown on the drawings, thus for example the rails, guides, switches and detaching blocks can be placed to the right or the left of the plane of the chain and the apparatus may comprise any number whatever of advertising panels, the working remaining always the same.

What I claim and desire to secure by Letters Patent of the United States is:

20 1. An advertising apparatus comprising a series of independent flexible panels having display matter on both faces but in relatively inverted position on the respective faces, transverse supports at opposite ends 25 of each panel, a rest upon which said panels are suspended by said transverse supports one behind the other in display position, endless traveling carriers at opposite margins of the panels, a trip device for maintaining the front panel in stationary position 30 during its display, means operated by said carrier for intermittently freeing said trip device and transferring said front panel to the carriers and means for detaching said 35 removed panel from the carriers and depositing it in inverted position upon the rest and at the back of the series.

2. An advertising apparatus comprising a series of independent flexible panels having 40 display matter on both faces but in relatively inverted position on the respective faces, transverse supports at opposite ends of each panel, a rest upon which said panels are suspended by said transverse supports 45 one behind the other in display position, endless traveling carriers at opposite margins of the panels, means for intermittently transferring the front panel of the series on the rest to said carriers, a transfer device 50 adjacent the rear of the rest, a coöperating detaching block engaged by the upper transverse support of the removed panel when brought to inverted position by said carrier, a second detaching block simultaneously engaged by the lower transverse supports 55 on said panel, whereby the disengaged inverted panel is deposited by said transfer device 60 upon said rest at the back of the series of panels.

3. An advertising apparatus comprising a series of independent flexible panels having display matter on both faces but in rela-

tively inverted position on the respective faces, transverse supports at opposite ends 65 of each panel, a rest upon which said panels are suspended by said transverse supports one behind the other in display position, endless traveling carriers at opposite margins of the panels, means for intermittently 70 transferring the front panel of the series on the rest to said carriers, a transfer device adjacent the rear of the rest, a coöperating detaching block engaged by the upper transverse support of the removed panel when 75 brought to inverted position by said carrier, a second detaching block simultaneously engaged by the lower transverse supports on said panel, whereby the disengaged inverted panel is deposited by said transfer device 80 and suspended by its upper transverse supports upon said rest at the back of the series of panels, said lower detaching block being pivoted and having a part lying in the path of the upper panel support by which the 85 block is moved into detaching position for the lower transverse support, and having also a second portion engaged by the lower support as it leaves the block whereby the latter is returned to non-detaching position. 90

4. In advertising apparatus of the type described, display panels having transverse, end supporting spindles, endless traveling chains for inverting and returning said panels to display position, and sprocket wheels 95 for said chains having teeth for engaging the chains and adjacent means to accommodate the panel supports.

5. In advertising apparatus of the type described, a series of flexible panels having 100 display matter on their opposite faces in relatively inverted position and having at their opposite ends supporting rods projecting beyond the margins of the panels on both sides, a rest on which said rod ends are supported in the display position of the panels, and intermittently operated mechanism for removing the front panel of the series from the rest, inverting the same and returning it to the rest at the back of the series, said 105 mechanism comprising endless chains arranged at the opposite margins of the panels and having links semicircular in shape and pivoted together at their ends to afford a series of open channels, the ends of the 110 supporting rods being delivered to and supported in said channels during the inverting travel of the chains, substantially as described.

In testimony whereof I have signed my 120 name to this specification, in the presence of two subscribing witnesses.

ALEXIS FRANÇOIS DE SAINT-ROMAIN.
